UNITED STATES PATENT OFFICE.

CHARLES L. HOLDEN, OF INDIANAPOLIS, INDIANA, ASSIGNOR OF ONE-HALF TO KNIGHT & JILLSON COMPANY, OF INDIANAPOLIS, INDIANA, A CORPORATION OF INDIANA.

FLUSHING-VALVE GUIDE.

No. 889,609.

Specification of Letters Patent.

Patented June 2, 1908.

Application filed January 27, 1906. Serial No. 298,157.

To all whom it may concern:

Be it known that I, CHARLES L. HOLDEN, a citizen of the United States, residing at Indianapolis, in the county of Marion and 5 State of Indiana, have invented new and useful Improvements in Flushing-Valve Guides; and I do declare the following to be a full, clear, and exact description of the invention, reference being had to the accompanying 10 drawings, and to the letters and figures of reference marked thereon, which form a part of this specification.

This invention relates to flushing valves of tanks that are used with water-closets, and 15 has reference particularly to the guides for the valves and to the supports of the guides.

Objects of the invention are to provide a stable and reliable support for the valve guide that is required for guiding the flushing 20 valves that are each provided with a valve stem; to provide a removable guide which may be easily detached from its support in order to substitute a new valve for an old one; to provide a self-adjusting guide 25 and support therefor that will enable the repairer to quickly replace the guide on its support with accuracy, so that the new valve may fit its seat exactly as it should do; and, further, to provide a guide construction 30 which will insure the replacement of the guide in the same position as that in which it had previously been used, without requiring measurements or time-occupying expedients.

35 The above-mentioned and minor objects are attained in the present invention, which consists in a flushing valve having a rigid valve-guide support cast integrally with the valve-seat body member so that the support 40 may be fitted accurately with respect to the valve-seat, the support having a guide-bar thereon, and a guide having a self-adjusting collar fitting the support and having a guide-groove to receive the guide-bar, with a set- 45 screw opposite to the guide-groove for securing the collar to the support; and, the invention consists further in the parts and the combinations and arrangements of parts, as hereinafter particularly described and 50 claimed.

Referring to the drawings, Figure 1 is a vertical longitudinal sectional view of a flushing tank with which the improved valve 55 guide and support, as preferably constructed, is connected and shown, the float lever being

in its lower position as when the inlet valve is open, and the flushing valve being closed; Fig. 2, a vertical central sectional view of the valve-seat body member and the guide support which also forms part of the overflow 60 pipe, the valve guide being mounted on its support; Fig. 3, a fragmentary perspective view of the guide support; Fig. 4, a perspective view of the guide and its appurtenances; and, Fig. 5, a horizontal sectional view ap- 65 proximately corresponding to the plane of the line A—A in Fig. 2.

Similar reference characters in the several figures of the drawings designate correspond- 70 ing elements or features.

In a practical embodiment of the invention, the improvement is used in connection with a flushing-tank *a* having an inlet-valve *b* operated by means of a float *c*. A valve-seat body *d* has a valve-seat *e* on which a 75 valve *f* operates in a well-known manner to control the flushing operations, the valve having a stem *g*, and a lever *h* is pivoted to the tank and is connected by a link *i* with the valve-stem. The body *d* being secured rig- 80 idly to the bottom of the tank, the flushing- pipe as usual is to be attached to the body beneath the tank. The body *d* is formed as a casting as usual, and the guide support *B* has a base *j*, all cast integral with the body *d*, 85 there being a duct *j'* in the support and its base communicating with the interior of the body *d* below the seat *e*, so that the support may be used as an overflow duct, as a matter of economy, although a separate overflow 90 pipe may be provided, if desired, in which case the top of the support *B* may be closed. The support *B* is upright and at the upper end thereof it has an annular external seat *k* which is formed accurately and is preferably 95 tapering, and at one side thereof the seat has an integral vertical guide-bar *l* that prefer- ably is wedge-shape, being narrower at its upper end. Screw threads *m* are cut in the upper end of the support, as shown, when it 100 is to be used as an overflow duct, and an overflow pipe *n* of suitable length has external screw threads *p* which correspond to the threads *m*, the pipe being thus screwed into the end of the support, and need not be accurately threaded, provided the pipe be fitted tightly into the end of the support.

The improved valve-guide comprises an arm *C* having at one end thereof an integral base collar *C'* which is accurately fitted to the 110

seat *k*, the finishing of both being done exactly by means of jigs and gages with respect to the seat *e*, so that any collar *C'* may be used on any seat *k* with precision. In one side of the collar *C'* a groove *q* is formed which corresponds to the shape of the guide-bar *l*, and a set-screw *r* is fitted into the opposite side of the collar so that the end of the set-screw may be forced against the seat *k* for securing the collar thereto. The opposite end of the arm *C* has a bore *s* therein that is true with the axis thereof in alinement with the axis of the bore of the seat *e*, and the stem *g* is guided in the bore. By the use of proper tools the bore may be made accurately in any number of guides, so that they may be interchangeable with the supports *B*, thus lessening the cost of manufacture below that required in fitting each guide separately to a crooked or inaccurate overflow pipe in the old way.

It is well known that the valves *f* deteriorate, being composed of rubber composition, and must be replaced by new valves. With the improved construction above-described, the set-screw may be loosened and the collar *C'* easily removed from its seat *k* after having disconnected the link *i*; then the stem *g* may be unscrewed from the valve. A new valve may then be applied to the stem, or a new stem may be supplied if required, and the collar may be replaced on its seat and secured by the set-screw, with the valve fairly in proper position on its seat. In replacing the collar, the guide-bar *l* will readily be received into the groove *q* so as to guide the arm *C* to the proper position, the guide-bar serving as a lock when the collar is seated to prevent displacement of the arm and the guide-bore *s*. In practical use the operations and results thereof are so well understood as to require no further description.

Having thus described the invention, what is claimed as new is—

1. In a flushing valve, the combination of a valve body member with a valve-seat therein, the body member having a valve guide support formed integral therewith, the support being hollow with the interior thereof in communication with the interior of the

body member below said valve seat, a portion of said support being tapered externally and having a guide-bar formed integrally on said tapered portion, and an annular collar seated removably on said tapered portion and having a groove receiving said guide-bar, with an arm rigid on said collar, and a valve on said seat with a stem guided by said arm. 55

2. In a flushing valve, the combination of a valve body member with a valve seat therein, the body member having a valve guide support formed integral therewith, the support being hollow with the interior thereof in communication with the interior of the body member below said valve-seat, a portion of said support being tapered externally and having a guide-bar formed integrally on said tapered portion, an overflow pipe attached removably to the top of said support, an annular collar seated removably on said tapered portion and having a groove receiving said guide-bar, and a set-screw in said collar engaging said tapered portion, with an arm rigid on said collar and a valve on said seat with a stem guided by said arm. 60 65 75

3. In a flushing valve, the combination of a valve body member with a valve-seat therein, the body member having a valve guide support formed integral therewith, the support being hollow with the interior thereof in communication with the interior of the body member below said valve-seat, a portion of said support being tapered externally and having a guide-bar formed integrally on said tapered portion, the interior of said tapered portion having screw threads, an overflow pipe having screw threads connected to the threads of the support, an annular collar seated removably on the tapered portion and having a groove receiving the guide-bar, and a set-screw in said collar engaging the tapered portion of the support, with an arm rigid on said collar, and a valve on said seat with a stem guided by said arm. 80 85 90

In testimony whereof, I affix my signature in presence of two witnesses.

CHARLES L. HOLDEN.
